UNITED STATES PATENT OFFICE.

GEORGE T. JOHNSON, OF COLUMBUS, OHIO, ASSIGNOR TO THE BUCKEYE STEEL CASTINGS COMPANY, OF COLUMBUS, OHIO.

BRAKE-HANGER BRACKET.

Application filed December 7, 1925. Serial No. 73,844.

This invention relates to car trucks and has special reference to the brake hanger brackets, the object in view being the provision of a bracket of such form as to possess maximum strength and furnish maximum support for the hanger pin and which may be produced at a minimum core-making cost and molding loss. This object is attained in a construction such as is illustrated in the accompanying drawings and the invention resides in certain novel features which will be hereinafter first fully described and then more particularly defined in the claims.

In the drawings, Figure 1 is a plan view 15 of a brake hanger bracket embodying the present invention;

Figure 2 is an end elevation of the same;

Figure 3 is a side elevation of the same;

Figure 4 is a vertical section on the line 20 4-4 of Figure 3, illustrating the nut lock for the right hand bracket,

Figure 5 is a view similar to Figure 4 but showing the opposite hand bracket.

The bracket is cast integral with the car 25 truck side frame, the side face of which is indicated by the line A-B in Figure 3 and a portion of which is shown at 1 in Figures 1 and 2. The bracket consists of a body or web 2 projecting laterally from the side 30 frame and inverted U-shape in cross section immediately adjacent the side frame, as shown in Figures 4 and 5. This inverted U-shape portion of the bracket is divided by a partition 3 to present two pockets 4 and 35 5 which respectively accommodate the nut 6 and one lobe of the hanger loop or stirrup 7. The lower end of the partition depends below the lower edges of the web 2, and it will be noted, upon reference to Figures 4 40 and 5, that the sides of the web are of unequal vertical extent so that at one side there is provided a space which facilitates the placing of the nut. It will also be noted that the lower edge of the partition presents 45 straight obliquely disposed surfaces 8 and 9 running to the longer and shorter side walls respectively of the web 2. The outer side wall of the pocket 5 is furnished by the inner end of a block 10. The top side of 50 the block 10 is disposed below the top of the U-shaped web or body 2, as indicated at 11, and ribs 13 extend along the top of the block at the sides thereof from the outer end of the web 2 to a point beyond the block where 55 they are united by an end wall 12, the

upper edge of which has the same outline as the upper side of the block 10 and is aligned therewith. The space between the block 10 and the end wall 12 constitutes a 60 pocket to receive the outer lobe of the hanger loop or stirrup 7. On the outer side of the end wall 12 is a lug 15 against which is engaged one side of the head 16 on the stirrup-retaining pin 17 which is inserted through aligned openings in the end wall 12, the 65 block 10, and the partition 3 to engage the lobes of the stirrup and thereby secure the same. The inner end of the pin extends into the pocket 2 and is threaded to engage the nut 6 in an obvious manner. Preferably, a lock washer 18 is fitted upon the pin 70 between the nut and the partition, one edge or corner portion of the washer being bent up against a side of the nut, as at 19, and an opposite edge portion of the washer being turned over the edge surface 8 in the right hand bracket or over the surface 9 in the left hand bracket. It is understood, of course, that two brackets are provided on each side frame and that they are disposed 75 on opposite sides of the vertical center line of the frame.

It will be observed that the ribs 13 do not extend the full length of the bracket and, consequently, there is a lessening of the 80 depth of this rib portion in the mold required for the production of the side frame with the bracket thereon. The peculiar arrangement and relation of the ribs 13 and the pockets 4 and 5 provides maximum 85 strength and bearing for the pin 17 and permits the casting to be made with a minimum core cost and molding loss.

The pin is supported at 12 and 3 outside of the hanger stirrup and full bearing for 90 supporting the pin between the lobes of the stirrup is provided by the block portion 10. The pockets 5 and 14 are provided for definite spacing and retention of the lobes of the stirrup.

Having fully described my invention what I claim as new and desire to secure by Letters-Patent, is:—

1. A brake hanger bracket for car trucks having spaced pockets at its inner end and another pocket near its outer end, the outer end being of less vertical extent than the inner end, and ribs extending along the top of the bracket from the outer end thereof to the inner pockets.

100

105

110

2. A brake hanger bracket for car trucks consisting of an inverted U-shaped web, a partition depending from the web between the ends thereof, a block extending from the web between the sides thereof, ribs extending along the block at the sides thereof to a point beyond the block, and an end wall uniting the ends of the ribs in spaced relation to the outer end of the block.
- 5 3. A brake hanger for car trucks consisting of an inverted U-shaped web, a partition depending from said web and having ob-

liquely disposed lower edge portions, a block extending outwardly from said web, an end wall beyond the outer end of the block, ribs connecting the end wall with the block, and a lug on the outer side of the end wall, there being aligned pin-receiving openings through the end wall, the block, and the partition.

15 20 In testimony whereof, I have signed this specification.

GEORGE T. JOHNSON.
